UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A BORDER FOR SILVERWARE OR SIMILAR ARTICLES.

SPECIFICATION forming part of Design No. 29,857, dated September 20, 1898.

Application filed August 17, 1898. Serial No. 688,816. Term of patent 3½ years.

To all whom it may concern:

Be it known that I, CHARLES OSBORNE, a citizen of the United States, residing in New York city, in the county and State of New York, have invented and produced a certain new and original Design for a Border for Silverware or Similar Articles, of which the following specification, with the accompanying drawing, is a full and exact description.

10 The drawing is a face view of a short length or section of the border.

The leading features of my design are the heavy ribbon or shell-like scrolls extending laterally from a small foliate rosette and the 15 lighter alternating reverse foliate scrolls flowing from the ribbons in opposite directions. Above the rosette are upwardly-curving foliate ornaments and scrolls.

20 The general character of the ornamentation may be described as being of that style known as "rocaille" or "rococo."

The foliate rosette occupies the center of a panel or section of the border, which may be repeated as often as required, and lies between the upturned ends of a pair of heavy 25 waved ribbon or shell scrolls. Above the

rosette are leaf-scrolls curving inwardly at the top and joined by a horizontally-disposed scroll of similar character inclosing other vertically-arranged ornaments, including a flattened volute on each side. From the outer ends of the ribbon scrolls extend a series of alternating scrolls, reversely arranged, terminating in each direction from the center rosette at a shell-like ornament surmounted by scrolls inclosing a plain open space.

30 The leaves, scrolls, ribbons, and tracery are in relief and offer a tasteful appearance of lightness and grace, produced at least in part by the alternating of the lighter foliate 35 scrolls with the heavier ribbon or shell-like ornaments.

I claim—

The design for a border for silverware or similar articles herein shown and described.

40 In testimony that I claim the invention above set forth I affix my signature in presence of two witnesses.

CHARLES OSBORNE.
